CLAIM

The ornamental design for a printer console housing for a hand-held calculator, substantially as shown and described.

DESCRIPTION

FIG. 1 is a front perspective view of a printer console housing for a hand-held calculator, showing my new design;

FIG. 2 is a rear perspective view thereof; and
FIG. 3 is a top plan view thereof.

The broken lines are shown for illustrative purposes only.

FIG. 1.

FIG. 2.

FIG. 3.
